[57] **CLAIM**

The ornamental design for a vanity cabinet, as shown and described.

DESCRIPTION

FIG. 1 is a front perspective view of a vanity cabinet showing my new design;

FIG. 2 is a front elevational view thereof;

FIG. 3 is a right side elevational view, the left side elevational view is a mirror image thereof;

FIG. 4 is a top plan view;

FIG. 5 is an enlarged fragmentary cross-sectional view taken along line 5—5 of FIG. 2;

FIG. 6 is an enlarged fragmentary cross-sectional view taken along lines 6—6 of FIG. 2;

FIG. 7 is an enlarged fragmentary cross-sectional view taken along line 7—7 of FIG. 2;

FIG. 8 is an enlarged fragmentary cross-sectional view taken along line 8—8 of FIG. 2;

FIG. 9 is an enlarged side elevational view of a door, the cabinet removed for convenience of illustration;

FIG. 10 is an enlarged cross-sectional view taken along line 10—10 of FIG. 9;

FIG. 11 is an enlarged side elevational view of a drawer, the cabinet removed for convenience of illustration;

FIG. 12 is an enlarged bottom plan view of FIG. 11; and, FIG. 13 is an enlarged fragmentary view of the pilasters. The rear of the cabinet is flat and plain.
